US0D1098324S

(12) **United States Design Patent** (10) Patent No.: **US D1,098,324 S**
(45) Date of Patent: ** Oct. 14, 2025

(54) **WEIGHTLIFTING BAR**

(71) Applicant: **Coulter Ventures, LLC.**, Columbus, OH (US)

(72) Inventors: **William Henniger**, Columbus, OH (US); **Steve Slater**, Lancaster, OH (US); **Ahmik Jones**, Upper Arlington, OH (US)

(73) Assignee: **Coulter Ventures, LLC.**, Columbus, OH (US)

(**) Term: **15 Years**

(21) Appl. No.: **29/860,866**

(22) Filed: **Nov. 23, 2022**

(51) LOC (15) Cl. **21-02**
(52) U.S. Cl. **D21/681**

(58) **Field of Classification Search**

USPC D21/662, 681, 690, 676, 686, 673

Primary Examiner — Jack Reickel

Assistant Examiner — Salamah Jordan

(74) Attorney, Agent, or Firm — Banner & Witcoff, Ltd.

(57) **CLAIM**

The ornamental design for a weightlifting bar as shown and described.

DESCRIPTION

FIG. 1 is a top, front, right perspective view of a first embodiment of a weightlifting bar showing our new design; FIG. 2 is a bottom, front, right perspective view thereof; FIG. 3 is a front view thereof; FIG. 4 is a rear view thereof; FIG. 5 is a top view thereof; FIG. 6 is a bottom view thereof; FIG. 7 is a right side view thereof; FIG. 8 is a left side view thereof; FIG. 9 is a top, front, right perspective view of a second embodiment of a weightlifting bar showing our new design; FIG. 10 is a bottom, front, right perspective view thereof; FIG. 11 is a front view thereof; FIG. 12 is a rear view thereof; FIG. 13 is a top view thereof; FIG. 14 is a bottom view thereof; FIG. 15 is a right side view thereof; and, FIG. 16 is a left side view thereof.

The broken lines immediately adjacent to the shaded area define the bounds of the claimed design and form no part thereof. The broken lines depicting the remainder of the weightlifting bar form no part of the claimed design.

1 Claim, 10 Drawing Sheets
